UNITED STATES PATENT OFFICE.

EDWARD CRAIG, OF ST. JOSEPH, MICHIGAN, ASSIGNOR TO SARANAC MACHINE CO., OF ST. JOSEPH, MICHIGAN, A CORPORATION OF MICHIGAN.

METAL-BOUND-BOX-BLANK-STAPLING MACHINE.

1,205,328.

Specification of Letters Patent. Patented Nov. 21, 1916.

Application filed June 16, 1910. Serial No. 567,185.

To all whom it may concern:

Be it known that I, EDWARD CRAIG, a citizen of the United States of America, and resident of St. Joseph, Berrien county, 5 Michigan, have invented a certain new and useful Improvement in Metal-Bound-Box-Blank-Stapling Machines, of which the following is a specification.

My invention relates to machinery for 10 making metal bound box blanks.

It relates more especially to the manufacture of metal bound boxes having sheet metal binding along the edges of the blank, the said binding having a flange by means 15 of which the end walls of the box are afterward secured in place.

My invention contemplates, broadly, a machine that is operative to drive staples through the sheet metal binding to fasten 20 the same to the different sections of the blank, and which will clench the staples upon the lower or inner surface of the sheet material, whereby each staple extends through the veneer of the blank and one 25 thickness of the metal binding. It also contemplates a machine for this purpose which will, in addition to driving staples through the sheet metal binding along the edges of the blank, insert flat staples to connect together 30 the edges of the different sections of the blank, which flat staples thereby serve as flexible hinges when the blank is folded, and prevent the corners of the box from opening.

It is also an object of my invention, in 35 addition to the above, to provide an improved feed mechanism for feeding the wire for the staples; to provide means whereby the mechanism which feeds the flat wire— 40 that is to say, the wire from which the flat staples are made—may be controlled at will to prevent driving of such staples at points where they are not needed; to provide an improved reversible clench-block arrangement, which is adapted to be controlled at 45 will to clench either prong or point of the staple, leaving the other prong or point unclenched; to provide a rubber or other yielding clench-block which will support a staple 50 while it is being driven, but which will prevent clenching thereof; and to provide certain details and features of improvement and combinations tending to increase the 55 general efficiency of a machine of this particular character.

To the foregoing and other useful ends, my invention consists in matters hereinafter set forth and claimed.

In the accompanying drawings—Figure 1 is a side elevation of a box blank stapling machine embodying the principles of my invention. Fig. 2 is a front elevation of the said machine. Fig. 3 is a plan of the same. Fig. 4 is a vertical section on line 4—4 in Fig. 2. Fig. 5 is an enlarged section on line 5—5 in Fig. 2. Fig. 6 is an enlarged section on line 6—6 in Fig. 2. Fig. 7 is a plan of the mechanism shown in Fig. 5. Fig. 8 is a vertical section on line 8—8 in Fig. 7. Fig. 9 is a rear elevation of the lower portion of 70 the mechanism shown in Fig. 7. Fig. 10 is a plan view of the mechanism shown in Fig. 6. Fig. 11 is a vertical section on line 11—11 in Fig. 10. Fig. 12 is a rear elevation of the lower portion of the mechanism shown in 75 Fig. 10. Fig. 13 is an enlarged fragmentary plan view of the reversible clench-block mechanism. Fig. 14 is a perspective of a metal bound box blank of the kind manufactured by my improved machine. Fig. 15. 80 is an enlarged section through a portion of said box blank, showing the staple inserted through the upper layer of the sheet metal binding, and clenched on the lower layer of said binding, whereby the staple extends 85 only through the upper layer of the binding and the veneer of the blank, but not through the lower or inner thickness of said binding. Fig. 16 is an enlarged fragmentary sectional view of a portion of the blank, showing one 90 of the staples which serve as hinges between the sections of the blank, and which hold the corners of the box together when the blank is folded. Fig. 17 is an enlarged cross section of one of the guides of the machine, showing one edge of the blank in cross section thereon, illustrating the manner in which the sheet metal binding of the blank is engaged by the guides to keep the blank moving in a straight direction. 100

As thus illustrated, my invention comprises a base A, upon which are mounted the vertical side members B of the frame. These side members are connected at their upper ends by means of a cross bar or member b and at a point below the same by a stationary bar or cross head b'. The reciprocating head C is of the usual form or construction, and is arranged to slide up and down in guide-ways provided in the mem- 105 110

bers B, being actuated by pitmen c which are connected with cams on the drive shaft D. The said shaft is operated and controlled in any suitable manner. A table E 5 is supported upon the members B, being adjustable up and down, and is provided with the horizontal and parallel guides e which extend longitudinally of the machine. Between these guides, clench-blocks F are provided and mounted upon the table E, being adjustable upon the latter, whereby the width of the blank may be varied at will. The staplers G are mounted above the guides e, and are adapted to drive staples made 10 from round wire. The staplers H are mounted above the clench blocks F, and are adapted to drive flat staples—that is to say, staples made from flat wire, or from flat strips of sheet metal. All of said staplers 15 are mounted upon the stationary cross head b', and are operated by the vertically reciprocating cross head C, in the usual and well known manner. The distance between the said staplers can be varied at will, depending 20 upon the width desired for the blanks. The blank to be made by this machine is shown in Fig. 14. It comprises four flexibly connected sections consisting of strips of veneer 1, 2, 3, 4, which have their edges 25 slightly spaced apart, and which are connected by the sheet metal binding I. This binding, it will be seen, is folded upon and around the side edges of the said blank, so as to provide upper and lower layers i, i', 30 which latter has a downwardly or inwardly extending flange i'', which flange is adapted to be stapled to the end walls of the box, in the well known manner. The said binding is provided with notches i''' at points 35 opposite the space between the edges of the veneer, whereby the blank can be easily folded around the end walls of the box. The sections of the blank are also connected by means of the staples J, which latter straddle 40 the cracks or spaces between the edges of the veneer, thus serving as hinges when the blank is folded, and preventing the corners of the box from gaping. The flat staples j, at one end of the blank, are left with their 45 outer points or prongs unbent, whereby they may be inserted through the other edge of the blank when the latter is folded to close the box.

As shown in Fig. 17, the binding I is engaged by the guide e, the latter being in the nature of a T-iron which presents one side or channel thereof to the folded edge portion of the sheet metal binding, thus supporting the blank and preventing sidewise 50 displacement thereof. Also the arrangement prevents distortion of the flanges i'' of the binding, as no weight or pressure is imposed on these flanges during the stapling operations. The staplers G drive the staples 55 K through the sheet metal binding and into

the veneer of the blank, as shown in Fig. 17, the prongs or points of said staples being clenched or bent upon the lower thickness i' of the said binding.

The staplers G are of the ordinary and 70 well known character, and may be of any suitable construction, except for the provision of the finger g that extends between the points of the staple to prevent the latter from being deflected toward each other 75 when they strike the metal of the binding. The said stapler comprises, therefore, as shown in Fig. 11, a driver g' secured to the cross head C, a staple former g'', and a loop bar g''', which coöperate to form and drive 80 the staple in the usual and well known manner. The staple former g'' has the finger g pivotally secured thereto, which finger is connected by a rod and spring g' with the cross head C, whereby the said staple former 85 is subject to spring pressure to permit it to cease moving downward when it strikes the work. A latch g'' is provided for locking the staple former to the staple driver, and a cam g''' serves to operate said latch and 90 thereby release the staple former and permit the staple driver to continue the downward motion alone—that is to say, without moving the staple former after the latter strikes the work. This is all well known and 95 well understood, and the finger g constitutes the only special provision, as this is necessary in view of the fact that the staples are driven through a layer of sheet metal. Were it not for this finger, which is automatically inserted between the points of the staple at the proper time, by the pressure of the spring g', the said staple might not puncture the metal, and would be liable to, 100 be deflected. The said finger, however, 105 keeps the points of the staple from being clenched or bent toward each other, and compels the same to puncture the metal and pass through the veneer of the blank. Then the staple points are bent upon the lower or 110 inner thickness of the metal binding, as shown in Fig. 15.

The staplers H are of similar construction, as shown in Fig. 5, except that they do not involve the finger g of the other staplers. 11 These staplers H are adapted to drive the wide flat staples J, j, and are actuated by the cross head b', all four staplers being operated simultaneously.

Each stapler G has a feed mechanism consisting of feed rolls L which are geared together, as shown in Fig. 6. A rock shaft M is mounted just back of the staplers and extends through the upper or larger of the feed rolls L, being supported in bracket 125 bearings m on the frame. The said shaft is provided with loose ratchet wheels l, and with crank arms l' which are keyed thereto, and which are provided with dogs l'' which engage the said ratchet wheels. The rock 130

shaft M is operated by a suitable connection N with the drive shaft D, in the usual and well known manner, whereby the shaft M is rocked or oscillated to cause the dogs 5 l^2 to actuate the ratchet wheels l and to thus operate the feed rolls L for feeding the wire to the staplers. The locking dogs O are arranged to engage the said ratchet wheels to prevent backward rotation of the shaft 10 and feed rolls. In this way the round wire is intermittently fed to the staplers G and the staples K are formed and driven.

The staplers H are each provided with feed mechanism of the kind shown in Fig. 15. Each feed mechanism comprises upper and lower feed rolls P, which are gear-connected together, the upper or larger roll being loosely mounted on the shaft M. The ratchet wheel Q, comprised in each feed 20 mechanism, is rigid with the upper roll, but loose on the shaft. The arms R are rigidly secured to said shaft M and are each provided with a dog r, which dogs engage the ratchet wheels Q. A cam or throw-out S is 25 associated with each dog r and arranged loosely upon the said shaft M, whereby the dogs r can be prevented from actuating the ratchet wheel Q, when it is desired to prevent the staplers H from driving the staples. 30 The cams or throw-outs S are connected by links s with the crank arms s' on a rock shaft s², whereby the said cams or throw-outs can be adjusted at will to prevent feeding of the flat wire and to thereby prevent 35 driving of the flat staples. The shaft s² is provided with a handle s³, which is connected by a spring s⁴ with the frame, said handle being adapted to work between the stops s⁵, s⁶, and held in normal position by 40 the said spring. The staplers H will drive the said staples, under normal conditions; but when the operator throws the handle s³ upward against the tension of the spring s⁴, the dogs r are prevented from actuating 45 the ratchet wheels, and as the flat wire is thus prevented from being fed, no flat staples are driven. In Fig. 5 the mechanism is shown in condition for feeding the flat wire, but in Fig. 1 the handle s³ is shown in 50 its raised position, whereby the dogs r are thrown out of engagement with the ratchet wheels Q, thus preventing a feeding of the flat wire. In this way the flat staples are driven where needed, and during the passage of intermediate portions of the blank no flat staples are driven, notwithstanding 55 that all four staplers are actuated each time the cross head C moves downward. In other words, the operator controls the staplers H 60 to drive the flat staples at the edges of the veneer, but not at points intermediate such edges.

The staplers H are each provided with a 65 clench-block F, as previously stated. The two clench-blocks are alike, and a descrip-

tion of one will be sufficient. The mechanism thereof is shown in Fig. 13. These clench-blocks are for clenching the points of the staples J, j. Each clench-block mechanism comprises a metal block f of a character to bend or deflect the point of the staple, and a rubber block f' associated therewith. There is also another metal block f² for the other point of the staple, and another rubber block f³ which is allotted thereto. The blocks f, f', are movable with the reciprocating rod f⁴, and the blocks f², f³ are movable with the rod f⁵. The two rods are controlled by a hand lever f⁶, and both rods are subject to spring tension tending normally to shift them to the left, as by means of springs f⁷, as shown in Fig. 2.

When the hand lever f⁶ is in the position shown in Fig. 13, then the metal blocks f, f², are opposite each other and both points of the staple will be clenched. Obviously, however, only one point of the staple j must be clenched, the other point being left unbent. This is accomplished by moving the hand lever f⁶ to the position shown in dotted lines in Fig. 13. This brings the rubber block f³ opposite the metal block f, and as the rubber will not clench the staple, one point thereof is left unbent, as shown in Fig. 14. If the staples j are to be applied to the other end of the blank, then the hand lever f⁶ is operated to shift the rubber block f' into a position opposite the metal block f², so that one end of the staple is clenched and the other left unbent, in the manner already 100 described. These staples can be driven at either end edge of the blank, and the overhanging portions of the staples left unbent, thus adapting the said staples for use in closing the box. The rubber blocks f', f³, are, therefore, adapted to alternate with each other, depending upon which end of the blank is to be supplied with the projecting staples. The said rubber blocks serve as yielding supports for the staples, to prevent 105 the same from falling down, but prevent clenching or bending thereof. It is obvious that various yielding supports or clench-block arrangements can be employed without departing from the spirit of my invention. 110

In the case of the staples H, as shown in Fig. 8, the loop bars T are provided with pointers or indicators t to enable the operator to properly position the blank to receive the staples J, j. When the blank is so adjusted that this pointer t is above the crack or slight space between the edge of the veneer, it is then in proper position to receive the staples J. Thus it is only necessary to bring the space between the section of the blank in alignment with the pointer or indicator t in order to properly locate the staples J. The staples j are located in a similar manner by pushing the blank along 115 120 125 130

until its edge is just a little beyond the pointer or indicator *t*, in a manner that will be readily understood.

The table *E* is raised and lowered by the hand wheel *e'* and screw *e²* through the medium of any suitable means. The gage *e³* on the machine will show the proper height for the table.

I do not limit myself to the exact construction shown and described. Broadly considered, my invention contemplates the driving of the staples through the sheet metal of the binding of a blank of this particular character, and the clenching of the staples on the lower or inner thickness of the binding, in the manner described. Prior to my invention, no machine had ever been proposed or constructed to drive staples through the metal of this binding and into the blank to secure the same thereto. No machine, of course, had ever been proposed or used which would not only staple the sheet metal to the blank, but which would also drive the flat staples to secure the edges of the blank together at the corners of the box. My invention is a pioneer in this and other respects, as will be readily understood.

What I claim as my invention is:

1. In a stapling machine, a plurality of staples, feed mechanisms therefor adapted to feed round wire to some staplers and flat wire to other staplers, means for operating said staplers simultaneously, means for operating the said feed mechanisms simultaneously, including a rock shaft that extends through all of said mechanisms, and devices for acting on the mechanisms for feeding the flat wire to prevent at will the operation thereof, without interfering with the feeding of the round wire by the other mechanisms on said shaft.

2. In a stapling machine, a plurality of feed mechanisms for feeding the material from which the staples are made, a rock shaft for operating said mechanisms, a second rock shaft, means operated by the second rock shaft to prevent at will the operation of one or more of said mechanisms, and means for manually operating said second rock shaft.

3. In a stapling machine, mechanism for clenching one prong or point of the staple without clenching the other, and means for controlling said mechanism to clamp both points.

4. In a stapling machine, means for clenching one prong or point of the staple, and a rubber block that supports the other prong or point and yields to prevent clenching thereof.

5. In a stapling machine, mechanism for clenching only one point of the staple, and means for reversing said mechanism, whereby either point can be clenched.

6. In a stapling machine, means for clenching one point of the staple, and a yielding support for the other point, to prevent clenching thereof.

7. In a metal bound blank stapling machine, means operative for stapling the sheet metal to the blank, along the edges thereof, means for applying flat staples to serve as hinges between the sections of the blank, and controlling means whereby the flat staples are properly located.

8. A machine for making box blanks having sheet material to form the sides of the box, and having sheet-metal binding extending lengthwise on the outer surface of the blank to flexibly connect together the sections along the side edges thereof, with right-angle inner flanges of said binding in position for stapling to box-heads after the blank is finished, comprising means for engaging said binding to hold the blank against displacement, constructed and arranged to support the blank without weight on said flanges, mechanism for inserting staples through the binding and the sheet material, and means to cause the clenching of the staples on the inner surface of the sheet material at one side of said flanges.

9. A machine for making box blanks having sheet material to form the sides of the box, and having sheet-metal binding extending lengthwise on the outer surface of the blank to flexibly connect together the sections along the side edges thereof, with right-angle inner flanges of said binding in position for stapling to box-heads after the blank is finished, comprising means for engaging said binding to hold the blank against displacement, constructed and arranged to support the blank without weight on said flanges, mechanism for inserting staples through the binding and the sheet material, said means including parallel stationary guides which engage the under side of said binding, and means to cause the clenching of the staples on the inner surface of the sheet material at one side of said flanges.

10. A machine for making box blanks having sheet material to form the sides of the box, and having sheet-metal binding extending lengthwise on the outer surface of the blank to flexibly connect together the sections along the side edges thereof, with right-angle inner flanges of said binding in position for stapling to box-heads after the blank is finished, comprising means for engaging said binding to hold the blank against displacement, constructed and arranged to support the blank without weight on said flanges, mechanism for inserting staples through the binding and the sheet material, said mechanism including staplers having means to insert the staples through

the binding, and means to cause the clenching of the staples on the inner surface of the sheet material at one side of said flanges.

11. A machine for making box blanks having sheet material to form the sides of the box, and having sheet-metal binding extending lengthwise on the outer surface of the blank to flexibly connect together the sections along the side edges thereof, with right-angle inner flanges of said binding in position for stapling to box-heads after the blank is finished, comprising means for engaging said binding to hold the blank against displacement, constructed and arranged to support the blank without weight on said flanges, mechanism for inserting staples through the binding and the sheet material, said means having portions to solidly support the binding and thereby adapt the said portions to be utilized as clench blocks for the staples, and means to cause the clenching of the staples on the inner surface of the sheet material at one side of said flanges.

12. A machine for making box blanks having sheet material to form the sides of the box, and having metal binding extending lengthwise of the blank to flexibly connect together the sections thereof, comprising means for engaging said binding to hold the blank against displacement, mechanism for stapling the binding to the sheet material, devices for applying flexible hinges to connect the sections of the blank, a reciprocating member for operating said mechanism and devices, and means to control said devices at will and without interfering with said mechanism.

13. A machine for making box blanks having sheet material to form the sides of the box, and having metal binding extending lengthwise of the blank to flexibly connect together the sections thereof, comprising means for engaging said binding to hold the blank against displacement, mechanism for stapling the binding to the sheet material, devices for applying flexible hinges to the blank, and means for gaging the position of the blank to receive said hinges.

14. A machine for making box blanks having sheet material to form the sides of the box, and having metal binding extending lengthwise on the outer surface of the blank to flexibly connect together the sections thereof, with right-angle inner flanges of said binding in position for stapling to box-heads after the blank is finished, comprising means for engaging said binding to hold the blank against displacement, constructed and arranged to support the blank without weight on said flanges, mechanism for stapling the binding to the sheet material, said mechanism being arranged to drive the staples with their heads extending longitudinally of said binding at one side of the vertical planes of said flanges.

15. A machine for making box-blanks by stapling sheet-metal binding to sheet material along the side edges of the blank, to flexibly connect together the sections of the blank, with the right-angle inner flanges of said binding in position for stapling to box-heads after the blank is finished, comprising staplers capable of driving staples through said binding into said sheet material, and means for so guiding the blank under said staplers that the staples are driven at one side of the vertical planes of said flanges, said means being so constructed and arranged that said flanges are not subject to pressure by said staplers, thereby to prevent distortion of said flanges.

16. A machine for making box-blanks by stapling sheet-metal binding to sheet material along the side edges of the blank, to flexibly connect together the sections of the blank, with the right-angle inner flanges of said binding in position for stapling to box-heads after the blank is finished, comprising staplers capable of driving staples through said binding into said sheet material, and means for so guiding the blank under said staplers that the staples are driven at one side of the vertical planes of said flanges, said means being so constructed and arranged that said flanges are not subject to pressure by said staplers, thereby to prevent distortion of said flanges, and said means having portions which engage the binding to prevent lateral displacement thereof from the edges of the sheet material.

17. A machine for making box-blanks by stapling sheet-metal binding to sheet material along the side edges of the blank, to flexibly connect together the sections of the blank, with the right-angle inner flanges of said binding in position for stapling to box-heads after the blank is finished, comprising staplers capable of driving staples through said binding into said sheet material, means for so guiding the blank under said staplers that the staples are driven at one side of the vertical planes of said flanges, said means being so constructed and arranged that said flanges are not subject to pressure by said staplers, thereby to prevent distortion of said flanges, and means to cause the clenching of the staples on the under surface of the sheet material at one side of said flanges.

18. A machine for making box-blanks by stapling sheet-metal binding to sheet material along the side edges of the blank, to flexibly connect together the sections of the blank, with the right-angle inner flanges of said binding in position for stapling to box-heads after the blank is finished, com-

prising staplers capable of driving staples through said binding into said sheet material, means for so guiding the blank under said staplers that the staples are driven at 5 one side of the vertical planes of said flanges, said means being so constructed and arranged that said flanges are not subject to pressure by said staplers, thereby to prevent distortion of said flanges, and devices 10 to apply flexible connections between the sections of the blank along a line or lines between said binding.

19. A machine for making box-blanks by 15 stapling sheet-metal binding to sheet material along the side edges of the blank, to flexibly connect together the sections of the blank, with the right-angle inner flanges of said binding in position for stapling to

box-heads after the blank is finished, comprising staplers capable of driving staples 20 through said binding into said sheet material, and means for so guiding the blank under said staplers that the staples are driven at one side of the vertical planes of said flanges, said means being so constructed 25 and arranged that said flanges are not subject to pressure by said staplers, thereby to prevent distortion of said flanges, said means engaging the binding outside of said flanges. 30

Signed by me at St. Joseph, Mich., this
31st day of May 1910.

EDWARD CRAIG.
